[57] CLAIM

The ornamental design for an electrical connector, as shown and described.

DESCRIPTION

FIG. 1 is a right side elevational view of an electrical connector showing my new design, the left side elevational view being a mirror image;

FIG. 2 is a top plan view thereof, the bottom plan view being a mirror image;

FIG. 3 is a front elevational view thereof; the broken line showing is included for the purpose of illustrating environmental elements only and forms no part of the claimed design; and

FIG. 4 is a rear elevational view thereof.
